CLAIM

The ornamental design for a connector, as shown and described.

DESCRIPTION

FIG. 1 is a side perspective view of a connector showing my new design;

FIG. 2 is a front elevation view thereof;

FIG. 3 is a rear elevation view thereof;

FIG. 4 is a first side view thereof;

FIG. 5 is a second side view thereof;

FIG. 6 is a top view thereof; and,

FIG. 7 is a bottom view thereof.

The dash-dash broken lines showing are included for the purpose of illustrating environmental structure that forms no part of the claimed design.

The dash-dash-long dash lines illustrate a symbolic break. The portion between the dash-dash-long dash lines forms no part of the claimed design.
